UNITED STATES PATENT OFFICE.

FERDINAND J. KITOWSKI, OF ST. CLOUD, MINNESOTA.

DEVICE FOR FORMING EYES ON SPRINGS.

1,252,123.

Specification of Letters Patent. Patented Jan. 1, 1918.

Application filed August 2, 1917. Serial No. 184,086.

To all whom it may concern.

Be it known that I, FERDINAND J. Kitowski, a citizen of the United States, and a resident of St. Cloud, in the county of Stearns and State of Minnesota, have invented a new and Improved Device for Forming Eyes on Springs, of which the following is a full, clear, and exact description.

My invention is more particularly intended for embodiment in a device for forming eyes on the springs of automobiles and other vehicles, although capable of forming eyes on articles other than springs.

An important object of my invention is to provide an eye-forming device of simple construction and easy of operation, and adapted to form eyes of different size or character on springs or the like.

The invention also has for its object to provide an eye-forming device improved in various particulars with respect to strength and efficiency and with a view to promote convenience and despatch in the positioning of the work, the forming of the eye, and the removal of the finished work.

An important object also is to promote despatch and simplicity in the adjustment of the device to produce eyes of varying character.

The nature of the invention and its advantages will clearly appear from the specific description following.

Reference is to be had to the accompanying drawings forming a part of this specification in which similar reference characters indicate corresponding parts in all the views, it being understood that the drawings are merely illustrative of one example of the invention.

Figure 1 is a plan view of an eye-forming device embodying my invention, parts being broken out;

Fig. 2 is a partly sectional plan view;

Fig. 3 is a side elevation partly in section as indicated by the irregular line 3-3, Fig. 1;

Fig. 4 is an end view;

Fig. 5 is a perspective view of the main frame with the hinge arm thereon omitted.

Fig. 6 is a transverse vertical section on the line 6-6, Fig. 3;

Fig. 7 is a perspective view of the base plate of a form that may be employed when the device is to be clamped in a vise.

In carrying out my invention in accordance with the illustrated example a suitable

base 10 is provided, here shown as consisting of a flat plate. The plate may be secured to a supporting structure in any suitable manner, there being indicated a cleat or flange 11 to secure the base in a vise. The main frame designated generally by the numeral 12 is swingably mounted on the base 10, said frame in the preferred form of the invention being generally of U-shape presenting upper and lower arms of different length. Connection between the frame 12 and the base 10 is preferably established by a threaded stud or fixed pin 13 depending from the bottom member or lower arm of the frame 12 near the free end thereof, and extending through a vertical hole 14 in the base 10, the said stud receiving a nut 15 and washer 16 at the under side of the base.

On the upper shorter arm 17 of the frame 12 is a vertically swinging arm or elongated member 18 constituting a swingable member of the frame, said arm being secured by suitable hinge means such as a transverse pin 19 extending through a fork or ears 18^a on the arm and through a pin hole 19^a in an enlargement 17^a on the arm 17. The outer end 18^b of said arm constitutes a handle. In the swingable member 18 is a vertical hole 20, there being an aligned hole 21 in the lower arm of the frame 12, said hole receiving and constituting bearings for the reduced ends 22, 23 of a former pin 24, and in the illustrated example of my invention which is the preferred form, the pin 24 is turnable, giving it the effect of a mandrel, the reduced ends 22, 23 constituting gudgeons turnable in the holes 20, 21 as bearings.

The swingable arm 18 permits of the ready placing and removal of the former pin 24. In order to firmly hold the arm 18 as to constitute a rigid part of the frame 12, latch means are provided which preferably consist of a vertical, spring-pressed latch 25 pivoted near its lower end as by a pin 26 between ears 27 rigid with the said arm 18. The numeral 29 indicates a spring formed by a strip of metal bearing near its upper end against a side of the latch 25 and secured at its lower end to the arm 18 by screws 30 or the like. The lower end of the latch below the pivot thereof is inturned as at 31 to effect a latching engagement to hold the arm 18 rigid.

The engagement of the latch is not directly with the arm 17 in the illustrated form of the invention, but is with an adjust-

able yoke 32 which has upper and lower side flanges 33 overlapping the upper and lower arms of the frame 12 to have guided movement on the latter. To adjust the yoke 32 on the frame 12 a threaded spindle 34 is provided which extends at its forward end through a hole 35 in the upright member 36 of the yoke 32 and is swiveled to said upright member in any suitable manner as 10 by means of collars 37 at opposite sides of said member, the collars being held by transverse pins 38. Said spindle 34 is turnable in a threaded hole 39 formed in the upright member 40 of the frame 12, there being a boss 40^a on the said frame through which the threaded hole 39 is formed. A suitable handle 41 is provided on the spindle 34 and by a turning of the spindle the threaded connection with the relatively fixed 20 frame 12 will cause an axial movement of the spindle for shifting the position of the slideable yoke 32.

The said yoke 32 carries the fulcrum for a clamping and forming lever 43 which is fulcrumed by a vertical pin 44. The end 45 of the lever 43 beyond the fulcrum pin is adapted to clamp an end of a spring A or the like between the said lever and the former pin 24 as clearly indicated in Figs. 30 1 and 2. The said spring A is positioned against a thrust plate 46 which is pivoted at one end on the base 10 as by a pin 47, the free end of said plate 46 lying adjacent to the pin 24. The plate 46 may be adjusted by a set screw 48 turning in a fixed standard 49 on the base 10 to vary the angular position of the spring.

With the described construction the spring A having been positioned as indicated in 40 Fig. 2 with its end extending beyond the thrust plate 46 to lie against a side of the pin 24 tangential to the latter, the lever 43 is given a slight movement on its fulcrum pin 44 to bring the head 45 into clamping 45 engagement with the spring adjacent to the end thereof, thus firmly gripping the spring between said lever and the forming pin or mandrel 24. With the spring thus firmly engaged by the lever 43 the operator, still 50 holding the lever 43, employs the same as a handle to swing said lever and the complete frame 12 with the spindle 34 through

approximately 270° or to the position indicated in dotted lines at the left of Fig. 2, or through such other angle as will complete 55 the forming of an eye a as indicated in dotted lines Fig. 2, on the spring. In the forming of the eye the frame 12 swings about the axis of its pivot pin or stud 13 which is coaxial with the pin 24 and thereby in the swinging of the frame, the end of the spring is bent about the said pin. Pins of various sizes or of different cross sections may be employed to produce eyes of different character. In changing the pin 60 24 the yoke 32 may be adjusted to bodily move the lever 43 and its fulcrum 44 to conform to the former pin 24 being employed.

I wish to state in conclusion that although the illustrated example constitutes a practical embodiment of my invention, I do not limit myself strictly to the mechanical details herein illustrated, since manifestly the same can be considerably varied without departure from the spirit of the invention as 75 defined in the appended claim.

Having thus described my invention I claim as new, and desire to secure by Letters Patent:

An eye-forming device including a swingable frame presenting a shorter and a longer arm, said arms being in rigid relation and spaced from each other, a hinged extension member on the said shorter arm, a forming pin engaged at one of its ends by the said hinged extension member and engaged at its opposite end with the longer arm of the frame, a yoke having sliding engagement with the said shorter and longer arms, a forming lever fulcrumed on the said slideable yoke and adapted to coöperate with the said forming pin, a latch carried by said hinged extension member to swing therewith, said latch being pivoted on said extension member to swing transversely to the plane of swinging of the said extension member, and a spring mounted on the extension member to bear against said latch and adapted to move the same into latching engagement with the said yoke when the extension member is positioned parallel with the longer arm of the frame. 90 95 100

FERDINAND J. KITOWSKI.
